UNITED STATES PATENT OFFICE.

LINCOLN MOSS, OF NEW YORK, N. Y., ASSIGNOR TO ROBINS CONVEYING BELT COMPANY, OF NEW YORK, N. Y., A CORPORATION OF NEW JERSEY.

UNLOADING, STORING, AND RECLAIMING APPARATUS.

No. 800,231.

Specification of Letters Patent.

Patented Sept. 26, 1905.

Application filed January 18, 1904. Serial No. 189,495.

To all whom it may concern:

Be it known that I, LINCOLN Moss, a citizen of the United States, and a resident of the borough of Manhattan, city, county, and State of New York, have invented certain new and useful Improvements in Unloading, Storing, and Reclaiming Apparatus, of which the following is a specification accompanied by drawings.

10 My invention relates to apparatus for unloading coal, ore, or other materials of like character from cars, barges, and the like, disposing said materials in storage, and reclaiming them therefrom.

15 In the handling of large quantities of any kind of material in bulk it is a desideratum of prime importance to provide apparatus by means of which such material may be unloaded from the cars, barges, or other carriers in 20 which it is delivered, placed in storage, and reclaimed therefrom at the desired capacity rate with a minimum of manual labor and apparatus and by the use of natural forces to as great an extent as possible. It is also important in providing this form of apparatus to 25 make use of such elements that the initial cost of the apparatus and the cost of operating shall be minimized.

The object of my invention is to provide a 30 system of apparatus by means of which large quantities of coal, ore, or other materials may be removed from vessels, cars, and the like and placed in storage at a rapid capacity rate and removed therefrom as required for use, 35 all this being accomplished with a minimum of apparatus and manual labor and a minimum of initial cost and cost of operation.

In attaining the objects above mentioned and other minor objects, which will hereinafter appear, I make use of the system of apparatus hereinafter described and claimed, the invention being illustrated in the accompanying drawings, in which there are also shown by way of comparison several other systems 45 of apparatus for accomplishing the same results.

In the drawings the preferred form of apparatus and the other forms illustrated for comparison therewith are shown in more or 50 less diagrammatic form.

Figure 1 is a plan view of the preferred form of apparatus; Fig. 2, a view in side elevation of the preferred form of apparatus, parts being broken away; Fig. 3, a view taken

from the left of Fig. 2; Fig. 4, a plan view of another system of apparatus; Fig. 5, an end elevation of the apparatus shown in Fig. 4; Fig. 6, a plan view of another system of apparatus; Fig. 7, an end elevation of the apparatus shown in Fig. 6; and Fig. 8 a diagrammatic view, on larger scale, of the tripper or deliverer employed in the preferred system of apparatus.

Referring to the drawings, in which corresponding parts are designated by similar characters of reference throughout, A designates the margin of a waterway, as a canal, over which the coal or other material to be stored is transported in vessels, one of which is diagrammatically indicated at B in position for unloading. A railway-track 1 is arranged parallel to the margin of the canal at a suitable distance therefrom for two electric cranes 2 2 to travel upon and unload the vessels in which the coal or other material is supplied. Two other tracks 3 extend at right angles from the track 1 and traverse the storage area C from end to end, each track being arranged almost midway between the median line of the storage-floor and one of its side walls. At the 70 points of juncture of the tracks 3 with the track 1 turn-tables 4 are provided to facilitate the passage of the locomotive-crane from the track 1 to the tracks 3 when occasion requires.

The storage area is preferably rectangular, or nearly so, in outline and is provided at its sides and ends with a retaining-wall 5, having gaps 6 therein at the end adjacent to the track 1 for the passage of the electric cranes 2. Along the median line of the storage area C there is provided a tunnel conveyer (indicated at 7) and having its head or discharge end disposed beyond the end of the storage-floor at 8, the head of the conveyer being supported above the level of the storage-floor in order to discharge into or upon any suitable receiver, as another conveyer, (not shown,) by means of which the material may be conveyed to points at which it is to be used. The tail or receiving end of the conveyer is disposed near the retaining-wall at the opposite end of the storage-floor, and thus the tunnel conveyer runs the entire length of the storage area.

Arranged parallel to the railway-track 1 and between it and the adjacent end of the storage area is an inclined conveyer 9, run-

ning underneath the receiving-hopper 10, which is fixed in position at a suitable distance from the canal to permit the locomotive-cranes 2 to hoist material from a vessel B and deposit it in the receiving-hopper for delivery upon the conveyer 9. The discharge end of the conveyer 9 is above a hopper 11 in a small tower 12 at the end of the storage-floor, and the material deposited in the hopper 10 is conveyed on the conveyer 9 to the hopper 11 in the tower 12 and discharged thereinto. The conveyer 9 is also provided with a traveling hopper 13, into which material may be deposited by the cranes when operating at other positions on the track 1 than those indicated.

The hopper 11 in the tower 12 discharges upon an elevated conveyer 14, which extends longitudinally of the storage area at a considerable height above it and directly over the tunnel conveyer 7. The elevated conveyer 14 comprises an inclined portion 15, adjacent to the tail end, and a horizontal portion 16, which is of slightly-greater length than the crest of a pile of material of approximately the same height as conveyer 14 and covering the storage area. Upon the horizontal portion 16 of the elevated conveyer a tripper or deliverer 17 of the form illustrated in Fig. 8 is arranged to travel. The tripper 17 comprises a hopper 18, having two lateral discharge-chutes 19, as shown in Fig. 3, supported upon the wheeled frame 20, which travels upon wheels 25, arranged at the sides of the conveyer. This form of tripper is well known in the art and is caused to travel along the rails 21 by the belt 22 of the conveyer 14, which is passed around pulleys 23 and 24, mounted in the wheeled frame 20 and connected by mechanism (not shown) with the supporting-wheels 25, which rest upon rails 21.

In the system of apparatus illustrated in Figs. 4 and 5 the storage area is provided with a tunnel conveyer 30, extending longitudinally thereof from the side A of the canal beyond the far end of the floor, and an elevated conveyer 32, similar to the elevated conveyer 14, already described, which extends from a tower 33, located at the side A of the canal and provided with stationary means for hoisting the material from the vessel B and depositing it in a hopper 34, which delivers to the conveyer 32. In this system of apparatus there are no railway-tracks traversing the storage area, but instead tracks 35 are provided at the sides of the storage area and a flying bridge is arranged to travel thereon. The flying bridge 36 carries a traveling "grab-bucket" 37, as shown in Fig. 5, and suitable means (not shown) is provided for moving the flying bridge on its tracks.

The system of apparatus illustrated in Figs. 6 and 7 is similar in many respects to that shown in Figs. 4 and 5; but while the storage area is provided with a tunnel conveyer 40, arranged in the median line, the elevated

conveyer 41 is placed at one side of the floor and extends from a tower 42 at the side A of the canal to the end of the storage-floor. The conveyer 41 is provided with a tripper which discharges upon a conveyer 43, supported on the flying bridge 44, which travels upon tracks 45, arranged at the sides of the storage-floor. The conveyer 43 on the traveling bridge operates the tripper, by means of which the material is distributed over the storage area in piles of the form shown in end elevation in Fig. 7, and the flying bridge also carries a traveling scraper-bucket 46, as best seen in Fig. 7.

In the operation of my improved system of apparatus the material removed from the vessel by the locomotive-cranes 2 is conveyed, by means of the inclined conveyer 9, to the elevated conveyer 14 and by means of the tripper operated by conveyer 14 is distributed over the storage-floor to form a pile of the form shown in side elevation in Fig. 2 and in end elevation in Fig. 3.

In reclaiming the material from storage by means of this apparatus the material at the middle of the pile discharges through gravity-chutes arranged over tunnel conveyer 7 and falls upon that conveyer, by which it is carried from beneath the storage pile and transferred to the conveyers or other carrying means, (not shown,) which deposit it wherever required for use. Thus without the use of other reclaiming means between thirty and forty per cent. of all the material in the pile may be reclaimed by utilizing the natural force of gravity and the tunnel conveyer, and two similar piles of material are left, one at either side of the tunnel conveyer and of the form indicated by dotted lines in Fig. 3. In order to reclaim this remaining material, the locomotive-cranes 2 are transferred from main track 1 to tracks 3, 3, running underneath the storage pile, and as the buckets of the cranes are capable of being swung through the arcs indicated by the dotted lines in Fig. 1 the material remaining in the storage pile can all be picked up by the cranes as they are advanced along the tracks and deposited upon the tunnel conveyer, a complete reclamation of the entire pile of material being thus effected.

In the operation of the apparatus shown in Figs. 4 and 5 the material is distributed over the storage area by means of a tripper provided on the elevated conveyer 32, and in reclaiming the material from storage the force of gravity is made use of to reclaim the material shown between the dotted lines in Fig. 5. To reclaim the material lying on either side of the tunnel conveyer, the traveling grab-bucket on the flying bridge is made use of, the material on one side being gathered up and deposited on the conveyer and then that on the other side.

In the storage of material by means of the

apparatus shown in Figs. 6 and 7 the material taken from the vessel B is carried by the conveyer 41 to the conveyer 43 on the flying bridge and is distributed over the pile by 5 means of the tripper operated by the latter conveyer, the bridge being movable on its tracks over the entire length of the storage area. The reclamation of the material from storage by means of this apparatus is effected 10 in part by gravity, as in the other two forms of the apparatus, and in part by means of the traveling scraper 46, which is carried by the flying bridge and is adapted to move transversely across the entire storage-floor, 15 as its movement is not impeded by the trestle of an elevated conveyer arranged above the storage-floor, as in the system of apparatus last described.

The advantages of my improved system 20 over the other two systems described herein, which, with perhaps slight modifications, are the systems ordinarily employed for this work, will be easily recognized. Comparing first the initial cost of the apparatus required 25 by my system with that necessitated by the others, it will be noted that I do away with the use of both the cumbersome and expensive flying bridge and the costly hoisting-tower and substitute for these two elements 30 the two comparatively light and inexpensive locomotive-crane. Furthermore, I reduce the lengths of belt conveyers or other forms of conveying apparatus, and hence their cost, to a minimum.

35 Considering the cost of maintenance and operation of the various systems, each of the locomotive-crane used by me is a one-man rig, while the hoisting-towers ordinarily used for unloading the material to be stored each 40 require at least two men for their operation. In addition, at least one man and often two are required to operate a flying bridge, and another man is needed to attend to the grab or scraper buckets used in reclaiming. Since 45 in the operation of my system the only power required is that employed in running two conveyers and the two locomotive-crane, it is apparent that very much greater power at a proportionately greater operating cost is required by a hoisting-tower, a flying bridge, the reclaiming bucket or buckets, and the conveyer system.

50 While the advantages of my system over all others now in use as regards original cost and expense of operation and maintenance are very great, the most important advantage of all really lies in the increased efficiency which I obtain. During all parts of the operations of unloading, storing, and reclaiming practically every element of my system is always in use and there is no superfluous machinery, no matter which of the various operations is being carried on. Both when unloading and storing and when reclaiming from 55 storage the two locomotive-crane may be

used. Both may be utilized for one purpose or one may be employed in unloading and the other in reclaiming. In all other systems some one or more of the various units must be idle, and hence useless, at times. Thus with the 70 other systems referred to herein the hoisting-tower is of no assistance in reclaiming. Hence during that operation a large and expensive piece of machinery is lying idle.

The question of obtaining large working 75 capacity by the use of a minimum amount of machinery and at a minimum expense is one of the most important points in the handling of coal, ore, and other similar materials. In the operation of my improved system two 80 units, the locomotive-crane, are used both for unloading and for reclaiming, and only four units, the two cranes and two conveyers, are used altogether. In the other systems, however, only one unit, the hoisting-tower, can 85 be used for unloading, and one unit, the grab or scraper bucket, can be used for reclaiming, yet a total of more units than I employ are required by the other systems.

Broadly stated, I obtain with my improved 90 system nearly double the working capacity at about two-thirds the initial cost and one-half the operating expense of any other system which, so far as I am aware, has been devised heretofore.

95 Obviously some features of this invention may be used without others and the invention may be embodied in widely-varying forms.

Therefore, without limiting myself to the construction shown and described nor enumerating equivalents, I claim, and desire to secure by Letters Patent, the following:

1. The combination with apparatus for unloading materials from cars, barges and the like, and means independent of said apparatus 105 for placing said materials in storage, of means for adapting said unloading apparatus for use in reclaiming the stored materials from storage.

110 2. The combination with apparatus for unloading materials from cars, barges and the like, and means independent of said apparatus for conveying said materials to a distance from the unloading apparatus and depositing them in storage, of means for adapting said 115 unloading apparatus for use in reclaiming the stored materials from storage.

3. The combination with movable apparatus for unloading materials from cars, barges and the like, and means independent of said apparatus for conveying said materials to storage, of means for transporting said unloading apparatus to the points of storage, to be used in reclaiming the stored materials from storage.

120 4. The combination with apparatus for unloading materials from cars, barges and the like, and means for conveying said materials to storage, of means for reclaiming a portion of the stored materials from storage, and means for adapting said unloading apparatus 125 130

to be used in reclaiming the remainder of said materials from storage.

5. The combination with movable apparatus for unloading materials from cars, barges and the like, and means for conveying said materials to storage at a distance from the points of unloading said materials, of means for reclaiming a portion of the stored materials from storage, and means for transporting said unloading apparatus to the points of storage to be used in reclaiming the remainder of said materials from storage.

6. In unloading, storing and reclaiming apparatus, the combination with apparatus for unloading materials from cars, barges and the like, and means for adapting said unloading apparatus to be used in reclaiming the stored materials from storage, of means for conveying said materials from points of unloading to points of storage, and separate means for elevating said materials and placing them in storage.

7. In unloading, storing and reclaiming apparatus, the combination with apparatus for unloading materials from cars, barges and the like, and means for adapting said unloading apparatus to be used in reclaiming from storage, of means for conveying said materials from points of unloading to points of storage, means for elevating said materials and plac-

ing them in storage, and means independent of the unloading apparatus for reclaiming the stored materials from storage.

8. In unloading, storing and reclaiming apparatus, the combination with a locomotive-crane adapted to be used for unloading materials from cars, barges and the like, and a conveyor for carrying said materials from points of unloading to storage, of means for transporting said locomotive-crane to the points of storage to be used in reclaiming the stored materials from storage.

9. In unloading, storing and reclaiming apparatus, the combination with a locomotive-crane adapted to be used for unloading materials from cars, barges and the like, and a conveyor for carrying said materials from points of unloading to storage, of means for reclaiming a portion of said materials from storage, and means for transporting said locomotive-crane to the points of storage to be used in reclaiming the remainder of the stored materials from storage.

In testimony whereof I have signed this specification in the presence of two subscribing witnesses.

LINCOLN MOSS.
